PULL ROD CARRIER

Allen M. Rossman, Wilmette, Ill.

Application May 10, 1939, Serial No. 272,865

24 Claims. (Cl. 74—522.5)

This invention relates to pull rod carriers and more particularly to means for supporting horizontally movable pull rods.

It is frequently necessary to transmit reciprocating motion or power great distances, as by means of very long rods or the like. In some instances a considerable amount of power is transmitted by the movement of the rod, and the distance involved may be very great, for instance, exceeding three thousand feet. This condition prevails, by way of example, in certain oil well districts wherein a number of oil wells are pumped by a single engine. The engine, through suitable mechanism, reciprocates a large number of pull rods each of which forms a connecting link between the source of power and a pumping jack located at an oil well, which may be at a considerable distance. To prevent dragging on the ground, each rod is supported by carriers spaced short distances apart, frequently approximately every twenty-five feet. These carriers, as heretofore used, generally were in the form of a stationary block having a groove on the top surface thereof in which the rod is supported, the rod sliding in the groove. In such a structure the groove must be exceedingly well lubricated and even then there is a very large amount of friction. This causes not only a loss of power, but also produces "jumpiness" in the rod, resulting in uneven operation and in great wear on the parts involved, and frequent breakage or snapping of the rods.

It is one of the objects of the present invention to provide carriers for a rod of this type, which carriers can be so arranged as to reduce the power loss to a minimum, and which will reduce the likelihood of snapping of the pull rod and which will not require constant attention for lubrication purposes.

In accordance with the teachings of the present invention a long pull rod of the above mentioned character is supported at short spaced intervals, say every twenty-five feet, by a swinging carrier which is anchored in the ground and which includes a saddle or the like for supporting the rod, said saddle being mounted by a series of links so that it moves in substantially a straight horizontal line throughout the length of reciprocating movement of the pull rod.

It is a further object of the present invention to provide such a straight line swinging carrier for a pull rod so constructed that the pull rod can be easily removed or replaced from any one carrier without requiring complicated adjustments of the carrier with respect to the pull rod.

It is a further object of the present invention to provide a swinging pull rod carrier of the above mentioned character wherein various parts may be made of simple pipes or rods with but a few bends therein.

It is a still further object of the present invention to provide a swinging pull rod support or carrier of such a construction as will readily utilize material such as is usually available as scrap material at places where oil wells are being drilled or operated.

It is a still further object of the present invention to provide a swinging pull rod carrier which is smooth in its action, does not require excessive attention or servicing, sturdy in construction and can withstand rough usage and adverse weather conditions without affecting operation of the carrier.

It is a still further object of the present invention to provide a pull rod carrier of the above mentioned type which may be supported on a simple foundation, consisting preferably of a single pipe suitably set in the ground, and wherein the supporting foundation plus the carrier will extend a minimum distance above the ground and yet be sufficiently elevated to prevent dragging of the rod on the ground due to the sag of the rod.

A pull rod of the above mentioned character must be supported at regular intervals along its length. In accordance with the teachings of the present invention it is one of the objects of the invention to provide a carrier which will support the rod at a plurality of points extending along a considerable length thereof so that the spacing between carriers may be increased above the previous minimum safe permissible distance between supports for the rod. This is accomplished, in one embodiment of the present invention, by providing a straight line supporting mechanism wherein the straight line operating points are spaced apart the full width of the straight line operating mechanism and wherein two or more straight line operating points which are spaced apart in the direction of the movement of the pull rod are both utilized to support the pull rod at spaced points. By this arrangement it is possible to increase the spacing between carriers.

While I have here spoken of a carrier for a pull rod in an oil pumping system, it is to be understood that this carrier can be used for supporting other types of pull rods in other instances as, for instance, pull rods for operating railroad switches or the like.

The attainment of the above and further objects of the present invention will be apparent from the following specification taken in conjunction with the accompanying drawings forming a part thereof.

In the drawings:

Figure 1 is a plan view, in partial section, of a pull rod carrier embodying the present invention, said view being a sectional view taken along the line 1—1 of Figure 2;

Figure 2 is an elevational view of the pull rod carrier embodying the present invention;

Figure 3 is an end view of the carrier of Figure 2;

Figure 4 is a fragmentary sectional view taken along the line 4—4 of Figure 2 and illustrating the manner of mounting the carrier;

Figure 5 is a diagrammatic plan view illustrating a single source of power transmitting motion to a plurality of pull rods extending to separate oil wells and each supported by carriers of the present invention;

Figure 6 is a plan view of another embodiment of the present invention;

Figure 7 is an elevational view of the carrier of Figure 6; and

Figure 8 is a sectional view taken along the line 8—8 of Figure 7.

Reference may now be had more particularly to Figures 1, 2 and 3 illustrating one embodiment of the present invention. A pull rod carrier is indicated by the reference numeral 1, said carrier supporting a pull rod 2 which reciprocates horizontally. The pull rod carrier is mounted by means of a post or foundation 4 which is rigidly anchored in the ground. At a suitable distance above the ground the post 4 has a supporting assembly secured thereto. The supporting assembly comprises upper and lower U-shaped rods 6 embracing the ground post 4 and separated by a U bolt 7. Between the upper and lower rods 6 there are secured two rods 9 and 10 which constitute the base of the pull rod carrier, the rods 9 and 10 being spaced apart on opposite sides of the post 4. The rods 6 are clamped tightly against the U bolt 7 and the rods 9 and 10 by J bolts 8, and the U bolt 7 clamps the assembly firmly to the support 4. Four wooden bearing blocks 12, 13, 14 and 15 are secured to the rods 9 and 10, as indicated in Figures 1 and 2, the bearing blocks being rigidly secured to the rods in any desired manner. Links 16 and 17 of identical shape and construction are rotatably mounted in the bearing blocks, the link 16 being mounted in the bearing blocks 12—14 and the link 17 in the bearing blocks 13—15. The link 16, comprises a rod having a horizontal portion 19 journaled in the wooden blocks 12—14 and then extending upwardly and inwardly to constitute the portion 20 which extends above the foundation and terminates in an inwardly bent horizontally extending portion 21 that supports and is journaled in a wooden bearing block 22. The link 17 is similarly bent and has its upper end journaled in a wood bearing block 23. The two bearing blocks 22—23 are connected by a link comprising two L-shaped rods 25—25' extending through holes in the bearing blocks 22—23. A lever 24, bent to the shape illustrated, is welded to the rods 25—25' and extends at right angles to the link comprising the rods 25—25' midway thereof. The lever 24 extends downwardly from the link 25—25' and at its lower end is bent in a direction at right angles to the rods 9—10, as indicated at 26 (Fig. 3). The portion 26 of the

lever 24 extends through a wooden carriage 28. The carriage 28 is, preferably, in the same vertical plane as are the blocks 22—23, as is apparent from Figure 3. To secure this result the lever 24 is bent to one side of the center as it extends from the bearing blocks 22—23, as is apparent from Figure 3.

From the above description it is apparent that there is provided a linkage comprising a four link chain of which the support for the fixed axes 30—31 (Fig. 2) constitutes one of the links. The lever 24 is the perpendicular bisector of a line adjoining the points 32—33, which is another link of the chain, and the axis 34 of the carriage 28 is on this perpendicular bisector. The distance between the fixed pivots 30—31, the lengths of the equal links 16—17, the distance between the movable pivots 32—33, and the distance of the point 34 from a line joining the pivot centers 32—33 are such that within the limits of motion the locus 35 of the point 34 is approximately a straight line. Since the pivots 30—31 are located at the same horizontal level, the locus of travel of the center 34 will be substantially horizontal. The proportions of the links may be made as shown in Figure 2 of the drawings. The carriage 28 is thus guided in a straight line by the links 16—17, and the lever 24 supported thereby. As the linkage moves from the position illustrated in full lines in Figure 2 to the position illustrated in dotted lines in that figure the links 16—17 move to the positions illustrated, and the center point 34 moves in substantially a straight horizontal line 35.

The carriage 28 has a V-shaped groove 36 extending lengthwise thereof which constitutes a saddle for the pull rod 2. The pull rod 2 rests freely in said groove and is supported by the carriage. As the pull rod is pulled to the right from the position illustrated in Figure 2 the linkage moves to the dotted line position. During said motion the carriage moves horizontally and continues to support the pull rod. The same type of motion takes place as the pull rod moves to the left from the position illustrated in Figure 2.

Stops are provided for limiting the extent of movement of the carriage 28. For this purpose one end of the rod 10 is bent inwardly and upwardly, as illustrated at 38 in Figures 1, 2 and 3. Likewise one end of the rod 9 is bent towards the center of the support and upwardly, as indicated at 39 in Figures 1, 2 and 3. The bent portions 38—39 are in the path of movement of the block 28 and thus limit the extent of movement of the block in each direction. The distance between these stops is such that the block 28 has a permissive movement slightly in excess of the amplitude of the movement of the pull rod 2.

Pull rods of the type illustrated in Figure 2 sometimes extend great distances. It is sometimes necessary temporarily to remove the rod from the carrier and let the rod rest on the ground as, for instance, to permit a vehicle or other load to pass over it. This can readily be done in the construction here illustrated, because the pull rod need merely be raised and moved to the right from the position illustrated in Figure 3 and then lowered to the ground. After the vehicle has passed over the rod the pull rod may be raised and replaced on the saddle in the block 28. At the time the pull rod is removed from the carrier the linkage may be in any position. Thereafter when the pull rod is replaced on the

carriage the carriage may not support the pull rod at the same place as previously. Upon the initial reciprocating movement of the pull rod the carriage may reach its limiting position in engagement with one or the other of the two stops 38-39 before the pull rod has completed its movement in the direction of its travel. Continued movement of the pull rod causes the pull rod to slide in the block 28 while the block 28 is held by the stop, so that the pull rod adjusts its position with respect to the block 28. Upon reversal of the direction of movement of the pull rod the carriage will move with it. Since the distance between the stops 38-39 permits a movement of the carriage slightly greater than the extent of reciprocating movement of the pull rod the block 28 will not engage the opposite stop.

It is to be noted that when the pull rod carrier reaches its limit of motion the direction of travel of the carriage 28 is still substantially a straight line, as may be seen by the locus 35 in Figure 2. Beyond its limit of travel, if the stops 38-39 were not provided, the direction of movement of the carriage would be somewhat upwardly rather than downwardly. This provides for stable operation of the linkage even if no stops were provided.

Reference may now be had more particularly to Figure 5 wherein I have illustrated a typical installation utilizing the pull rod carriers of the present invention. In this installation a structure known as a "power" is illustrated at 43. This "power" is rotated by means of a steam engine or other rotating means and includes a disc or the like 44 mounted on the "power" by means of an eccentric, and reciprocating a plurality of pull rods 2 that extend to individual wells, such as oil wells, 46. The pull rods are supported at frequent intervals, which may be twenty-five or so feet apart, by pull rod carriers 1. The various pull rods may be of different lengths, as illustrated, from very short lengths up to several thousand feet in length.

I have discovered that the movable pivot 34 of the carrier shown in Figures 1, 2 and 3 may be made fixed to constitute the point of support of the carrier, and the pivots 30-31 may be made movable to move in a straight line and constitute two supporting points for the pull rod. This is illustrated with a linkage of somewhat different proportions in Figures 6, 7 and 8, to which reference may now be had. In this construction the pull rod is again indicated by the reference numeral 2 and is supported by a carrier which is mounted in place by a post 4, rigidly set in the ground in any desired manner. The post 4 has a wooden bearing block 49 rigidly secured thereto. The pull rod carrier includes a fixed pivot 50 and four movable pivots 51, 52, 53 and 54. A rod or like support 55 is pivotally mounted at 50 and is bent, as indicated at 56, to constitute a support for two bearing blocks 57-58 that are rigidly mounted on the portion 56 of the rod 55. These blocks constitute the bearings for the movable pivots 52-53. Identical links 60-61 connect the pivots 51-52 and 53-54 respectively.

The link 61 is Z-shaped, as may be seen from Figures 6 and 8, and includes a vertically extending diagonal portion 62, a horizontal upper portion 63 the center of which constitutes the pivot 53, and a horizontal lower portion 64 the center of which constitutes the pivot 54. The upper portion 63 is journaled in the bearing block 58, and the lower portion 64 is journaled in a bear-

ing block 65. A similar bearing block 66 is journaled to the corresponding part of the link 60. The bearing blocks 65-66 are secured together in fixed spaced relationship by a tie member 67 extending through the bearing blocks and to which the blocks are locked. The tie member extends beyond the blocks 65-66 and carries carriages 68-69 at its opposite ends. These carriages are wooden blocks each having a V-shaped groove at the top thereof, in which grooves the pull rod 2 rests. In addition stop blocks 70-71 are also mounted upon the tie member 67, which stop blocks may also support the pull rod 2. The bearing blocks 65-66 may also bear against and support the pull rod 2.

When the pull rod is pulled in one direction or the other it draws the carrier mechanism with it. The rod 55 pivots about the fixed pivot 50 so that the two movable pivots 52-53 move in arcs of circles about the pivot 50 as a center. As the rod is pulled to the left from the position illustrated in Figure 7 the support 55 and with it the two movable pivots 52-53 swing counter-clockwise. At the same time the continuity of the pull rod maintains the bearing blocks 65-66 in horizontal alignment so that the links 60-61 swing about the pivots 52-53. The spacing between the pivots 50, 52 and 53, the lengths of the links 60-61 and the spacing of the movable pivots 51 and 54 are such that the pivots 51 and 54 move in substantially a straight line extending lengthwise of the pull rod. The pivot point 50 is located exactly on the perpendicular bisector of a line joining the pivot centers 52-53 as seen in Figure 7.

The pull rod may be lifted from the carrier and lowered to the ground so as to permit a vehicle or the like to pass over it. Upon replacement of the pull rod upon the carrier the pull rod may not be supported by the carrier at the same points on the pull rod as previously. Upon movement of the pull rod one or the other of the two stop blocks 70-71 limit the movement of the carrier. The stop 71 abuts against the support 4 if the continued movement of the pull rod to the left is excessive with respect to the position of the carrier. Additional movement of the pull rod to the left causes the pull rod to slide on the carrier supports without further movement of the carrier. Upon reversal of movement of the pull rod the carrier moves with the rod, the pull rod having thus been moved to its proper position with respect to the bearing blocks 68-69. In a like manner the stop block 70 limits the movement of the carrier to the right from the position illustrated in Figure 7 to a position wherein the stop block 70 engages the bearing block 49. When the carrier is in its mid position, as illustrated in Figure 7, the distance between the stop 71 and the support 4 is equal to the distance between the stop 70 and the bearing block 49, and is slightly more than half of the maximum range of travel of the pull rod in either direction.

It is possible to support the pull rod directly upon the bearing blocks 65-66 without provision of the cantilever extensions 75-76 and without the blocks 68-69. However, by provision of the extensions 75 and 76 and the saddles 68-69 the points of support for the pull rod are spaced further apart and it is thus possible to increase the distance between adjacent carriers for the pull rod. By way of example, in one construction the distance between movable pivots 51-54 is approximately 7½ feet. Thus for each carrier there

is provided two points of support $7\frac{1}{2}$ feet apart. The extensions 75-76 may each be approximately $2\frac{1}{2}$ feet long thus providing supports 68-68 $12\frac{1}{2}$ feet apart or, supports $6\frac{1}{4}$ feet on each side of the post 4. If it is desired to support the pull rod at twenty-five foot intervals then the distance between adjacent carriers, measured at the post 4 may be made $37\frac{1}{2}$ feet. Thus two carriers will suffice for every seventy-five feet of pull rod length while the maximum distance between the supporting blocks 68 of adjacent carriers is twenty-five feet. By the construction illustrated in Figure 2 a twenty-five foot spacing between supports for the pull rod, necessitated three carriers for every seventy-five feet of pull rod length.

For a further description of the principles of the straight line mechanism disclosed in Figure 7 and of the laws of motion whereby the proportions of the links and the distances between the pivots may be varied to produce a different amplitude of motion, reference may be had to my pending application, Serial No. 224,862, filed August 15, 1938. In the aforesaid application the straight line mechanism is shown as pivotally supported at two points corresponding to the points 51 and 54 as fixed points, and the point 50 corresponds to the straight line point in the above referred to application.

It is understood that many of the structural features of the carriers of Figures 2 and 7 are interchangeable. For instance, the members that locate the pivot point 34 on the perpendicular bisector of a line between the pivots 32-33 of Figure 2 and the corresponding member that locates the pivots 50, 52 and 53 in proper relative positions in the carrier of Figure 7, may be interchanged. Likewise, as there is shown a cantilever member interposed between the straight line moving pivots and the pull rod 2 of Figure 7 so a beam or the like may be interposed between the pivot 34 and the pull rod 2 of Figure 2 so that the beam supported by the pivot 34 in turn supports the rod 2 at two places spaced on the opposite side of the center 34, the beam extending on each side of the pivot 34 as a cantilever. If desired, the member 28 of Figure 2 may be very much elongated to constitute a cantilever support for the rod 2 at opposite sides of the pivot 34, the supports for the pull rod being an appreciable distance apart.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new and desire to secure by Letters Patent is:

1. In combination with a longitudinally reciprocating pull rod, a support, a carrier comprising a straight line linkage including a plurality of links pivoted together and pivoted on the support, said linkage supporting the pull rod at a straight line motion point of the linkage, said straight line motion point having an amplitude of substantially straight line motion exceeding the amplitude of motion of the pull rod, and said pull rod being slidable with respect to its straight line supporting point.

2. A pull rod carrier comprising a supporting column, a pair of parallel horizontally extending members mounted on said column on opposite sides thereof, a pair of aligned bearings on said members on one side of the column, a second pair of aligned bearings on said members on the

opposite side of the column, a link pivoted in one of said pairs of bearings, a second link pivoted in the second pair of bearings, a third link pivotally connecting the two previously mentioned links, said third link having a pull rod supporting part located on the perpendicular bisector thereof and between the two first named links.

3. A pull rod carrier comprising a supporting column, a pair of parallel horizontally extending members mounted on said column on opposite sides thereof, a pair of aligned bearings on said members on one side of the column, a second pair of aligned bearings on said members on the opposite side of the column, a link pivoted in one of said pairs of bearings, a second link pivoted in the second pair of bearings, a third link pivotally connecting the two previously mentioned links, said third link having a pull rod supporting part located on the perpendicular bisector thereof and between the two first named links, and means associated with each of said horizontally extending members for limiting the extent of turning of said links.

10 4. In combination with a longitudinally reciprocating pull rod, a pivotally mounted straight line motion linkage mechanism, a beam carried by the straight line motion mechanism and movable therewith in a straight line and extending 15 therefrom as a cantilever in at least one direction, the pull rod being supported at the cantilever end of the beam.

20 5. A carrier comprising a four link chain pivoted together to constitute a quadrilateral, two 25 of the links being of equal effective lengths and two being of unequal lengths, a stationary pivot about which one of the two unequal links is pivoted, said pivot being spaced from said unequal link and located on the perpendicular bisector 30 thereof, and means for maintaining the other unequal link of the quadrilateral substantially horizontal during swinging of the carrier about said stationary pivot.

35 6. In combination, a carrier comprising a four link chain pivoted together to constitute a quadrilateral, two opposite links being of equal effective lengths and the other two of unequal lengths, supporting means comprising a pivot spaced a fixed distance from the shorter of the unequal 40 links and equal distances from the pivots of said shorter link, the longer of the unequal links constituting another support means, means mounting the four link chain at one of said supporting means, and a longitudinally reciprocating load 45 supported by the other supporting means, the longer of the unequal links being parallel to the direction of motion of the load.

50 7. An oil pumping system including an oil pumping mechanism, a source of power, and a reciprocating pull rod connecting the two, pull rod carriers supporting the rod at spaced intervals along its length from the source of power to the mechanism, each of said carriers comprising a pivoted linkage having a part thereof constrained to a straight line horizontal motion, means supported by said straight line motion part of each carrier and supporting said rod at a plurality of points spaced from one another in excess of 10% of the spacing between carriers.

55 8. Apparatus of the character described comprising a base member, upstanding legs pivotally supported in spaced relation by said base member, a depending member pivotally supported intermediate the upper ends of said legs, a support 60 affixed to said depending member adapted to re-

70

ciprocate in a substantially straight line and means for positively stopping the motion of said support at fixed points.

9. A pull rod carrier comprising a base, a cross member pivotally supported at each end by legs of equal length which are pivotally attached to said base, said cross member having a part which is rigidly fixed to the rest of the cross member and depending perpendicularly from the mid point of a line joining the pivots at the ends of the cross member, a pull rod support pivoted at a lower point of said depending part adapted to reciprocate in a substantially straight line motion, and stop members adapted to stop the reciprocating motion of said support at fixed points.

10. Apparatus for supporting a horizontal longitudinally reciprocating pull rod intermediate its ends to prevent excessive sagging thereof, said apparatus including a straight line motion mechanism comprising a pair of links pivoted at one end to swing about parallel spaced stationary horizontal axes, bearing blocks on the opposite ends of said links, a third link connecting the two blocks and journalled thereby to the first links to pivot with respect thereto, said third link including a member extending below the blocks, a pull rod support pivoted to said member at a point below the pivots of the third link and at a substantial straight line motion point of the third link, said support having means for holding a pull rod resting thereon in a position such that the vertical plane determined by the longitudinal axes of the pull rod passes centrally through the blocks.

11. Apparatus for supporting a horizontal longitudinally reciprocating pull rod intermediate its ends to prevent excessive sagging thereof, said apparatus including a straight line motion mechanism comprising a pair of links pivoted at one end to swing about parallel spaced stationary horizontal axes, bearing blocks on the opposite ends of said links, a third link connecting the two blocks and journalled thereby to the first links to pivot with respect thereto, said third link including a member extending below the blocks, a pull rod support pivoted to said member at a point below the pivots of the third link and at a substantial straight line motion point of the third link, said apparatus being open at one side and embracing but not surrounding the pull rod support whereby a pull rod is removable from the support and from the apparatus by lifting and moving the rod sideways to permit lowering of the assembled rod from the apparatus.

12. Apparatus for supporting a longitudinally reciprocating pull rod intermediate its ends to prevent excessive sagging thereof, said apparatus including four bearing blocks spaced from one another to constitute corners of a horizontal rectangle, a first link journalled in two adjacent blocks to swing about a horizontal axis, a second link similar to the first link and of an equal length journalled in the other blocks about a horizontal axis parallel to and at the same level as the first mentioned axis, both links extending upwardly from said axes, bearing blocks journalled on the upper ends of said links about axes parallel to the first mentioned axes, a third link connecting the two last mentioned blocks and supported thereby and including a member extending below the last mentioned blocks, a pull rod support pivoted to said member about an axis below and midway between the two axes of the last mentioned blocks and at a substantial straight line motion point of the third link, said

support moving in a substantially straight line located centrally above and lengthwise of the rectangle formed by the four first mentioned bearing blocks.

- 5 13. In a system wherein power is transmitted from a power source to a place of utilization by a reciprocating substantially horizontal pull rod of such length as to require support between the source of power and the place of utilization to prevent excessive sagging of the rod, a pull rod carrier comprising a pair of equal links pivoted to swing about spaced fixed parallel pivots, a member pivotally joining the links to swing about two parallel movable pivots above the fixed pivots, the distance between the movable pivot axes being substantially less than the distance between the fixed pivot axes, each of said links being in the form of rods bent at the ends to form upper and lower parallel horizontally extending portions constituting the bearing shanks for the link pivots, and said parallel portions being joined at one end by an intermediate portion to form three sides of a polygon one side of which is open, said joining member having a depending portion, a pull rod support pivoted to the depending portion at a substantially straight line motion point thereof below and an equal distance from the movable pivots, said carrier embracing but not surrounding the support whereby a pull rod is removable from the support and from the carrier by moving the rod sideways through the open side of said polygon.

14. Apparatus of the character described comprising a base member, legs pivotally supported at one end in spaced relation by said base member, a member pivotally supported intermediate the opposite ends of the legs, a support affixed to said last member at a place on the perpendicular bisector of a line joining the pivots of said last member and at a distance from the said pivots of the last member greater than the distance between those pivots, and adapted to reciprocate in a substantially straight line, and means for positively stopping the motion of said support at fixed points.

15. A device of the character described comprising a pair of upstanding arms mounted at their lower ends on fixed pivots, a support suspended between said arms by movable pivots in such manner as to be capable of oscillating for a limited distance along a substantially straight line, said support being adapted to carry a reciprocable rod on its upper surface.

16. In combination with a reciprocable pull rod, a pull rod carrier for supporting the rod, said carrier including a support upon which said rod is adapted to rest, said support being suspended by linkage comprising a series of links pivotally connected and which guides said support to oscillate along a substantially straight line, the carrier being open on one side and the pull rod being supported on said support so that the rod may be removed from the support and carrier by lifting and moving the rod laterally to permit lowering of the rod from the carrier.

17. In a system wherein power is transmitted from a power source to a place of utilization by a reciprocating substantially horizontal pull rod of such length as to require support between the source of power and the place of utilization to prevent excessive sagging of the rod, a pull rod carrier comprising a pair of equal links pivoted to swing about spaced fixed parallel pivots, each of the links being in the form of rods bent at the ends to form upper and lower parallel horizon-

tally extending portions connected by an intermediate portion at an acute angle to the lower portion to form three sides of a quadrilateral the fourth side of which is open, bearing blocks on the upper portions of the links, a member joining the bearing blocks and supported thereby to swing about spaced parallel movable pivots above and closer together than the fixed pivots, said member having a depending portion at an inclination to a vertical plane at right angles to the movable pivots, a pull rod support pivoted to the depending portion at a substantially straight line motion point thereof below and at an equal distance from the movable pivots and above the fixed pivots and with its longitudinal center line in a vertical plane passing through both bearing blocks, said carrier embracing but not surrounding the support and being open at one side whereby a pull rod is removable from the support and from the carrier by moving the rod sideways through the open side of the quadrilateral.

18. A carrier for a horizontally reciprocable pull rod, said carrier comprising a pair of pivoted arms, a swinging member pivotally connecting the arms, a pull rod support pivoted to the member at a substantially straight line motion point thereof, each arm including a horizontal bearing shank, the pivotal connection between each arm and the swinging member comprising a block having non-intersecting holes formed therein at right angles to one another, the bearing shank of the arm extending through one of the holes, one end of the swinging member extending through and being supported in the other hole, the axis of said other hole being horizontal and parallel to the direction of straight line motion of the support, and said support being located in a position centrally intersected by the vertical plane determined by the axis of said other hole whereby it can hold a pull rod with its longitudinal axis in the same vertical plane as the vertical plane determined by the axis of said other hole.

19. Apparatus of the character described comprising a pivotally supported member, a point on which moves along a substantially straight line when said member is oscillated, a support affixed to said member at said point and upon which a reciprocable member of predetermined stroke is adapted to be slidably supported, and positive means for preventing said first member from oscillating beyond a predetermined distance slightly in excess of the limits of the stroke of said reciprocable member.

20. Apparatus of the character described com-

prising upstanding legs pivotally supported in spaced relation, a depending member pivotally supported intermediate the upper ends of said legs, a support affixed to said depending member adapted to reciprocate in a substantially straight line and upon which a reciprocable member of predetermined stroke is adapted to be slidably supported, and means for stopping the reciprocation of said support at points slightly beyond the limits of the stroke of said reciprocable member.

21. A device of the character described comprising a pair of upstanding arms mounted at their lower ends on fixed pivots, a support suspended between said arms by movable pivots in such manner as to be capable of oscillating for a limited distance along a substantially straight line, said support being adapted to freely carry a reciprocable rod on its upper surface.

22. A device of the character described comprising a pair of upstanding arms mounted at their lower ends on fixed pivots, means suspended between said arms by movable pivots for supporting a reciprocable rod, said means being capable of oscillating over a limited distance along a substantially straight line, said means also being adapted to freely support said rod without permitting sliding when said means oscillates within the limits of its substantially straight line motion.

23. In combination with a substantially horizontal reciprocable power transmitting pull rod and a plurality of carriers spaced from one another in a direction lengthwise of the rod and adapted to freely support said rod at a plurality of points, said carriers comprising a plurality of pivotally interconnected links having supports for said rod which are adapted to oscillate along a substantially straight line, and on which said rod is slidable, and stop limiting means for centering each carrier support with respect to the rod in the direction of reciprocation of the rod.

24. A device of the character described comprising a plurality of links pivotally connected together to form a linkage having a point thereon adapted to oscillate over a limited distance along a substantially straight line, supporting means fastened to said linkage at said point for freely supporting a reciprocable rod line, and stop limiting means for centering said supporting means with respect to a reciprocable rod line supported thereby and in the direction of reciprocation of such rod line.
